UNITED STATES PATENT OFFICE.

HARRY H. VICKERS, OF ASTORIA, NEW YORK, ASSIGNOR, BY MESNE ASSIGNMENTS, TO UNDERWOOD COMPUTING MACHINE COMPANY, OF NEW YORK, N. Y., A CORPORATION OF NEW YORK.

COMBINED TYPE-WRITING AND COMPUTING MACHINE.

1,278,062.

Specification of Letters Patent.

Patented Sept. 3, 1918.

Application filed February 6, 1915. Serial No. 6,434.

To all whom it may concern:

Be it known that I, HARRY H. VICKERS, a citizen of the United States, residing in Astoria, Long Island, in the county of 5 Queens and State of New York, have invented certain new and useful Improvements in Combined Type-Writing and Computing Machines, of which the following is a specification.

10 My invention relates to computing machines, and is herein disclosed as applied to a combined typewriting and computing machine of the Underwood-Hanson type, wherein, as the typewriter carriage travels 15 along, the numeral keys of the typewriter, one after another, set up index pins which are arranged on denominational computation members, thus representing the digits in the numbers written and to be computed. 20 After being thus written and set up, the numbers are carried into a totalizer, or set of computing wheels.

Such combined typewriting and computing machines are used for a great variety 25 of work, and it is found essential in making a machine that will stand commercial use, that most of the parts of the machine be solid and built to stay in place. It is awkward, and inadvisable mechanically, to add 30 either permanently or temporarily, computing wheels to a totalizer which is already complete. Yet on the other hand, it is advantageous to sometimes have a totalizer which is small, thereby covering only a 35 small number of letter-spaces in the travel of the typewriter carriage, this being so because only such small totalizers are adapted to cross-add numbers in adjacent columns where said columns cover a few 40 decimal spaces such as thousands, hundreds of thousands or millions. On the other hand, for a machine which is adapted to general commercial use in miscellaneous offices, it is advisable and it is desirable to have a machine 45 which shall be able to add to or beyond hundreds of millions.

My invention is especially directed toward enabling a totalizer comprising a very long series of computing wheels to be, so 50 far as the numeral keys are concerned, cut down to a totalizer having a smaller number of wheels, so that cross-adding can be done in adjacent columns on the typewriter

without any danger of confusing digits written in one column with digits written in another column.

The possibility of such confusion arises from the fact that in most combined typewriting and computing machines, there is a denomination selector traveling 60 comitantly with the typewriter carriage, and if it is desired to cross-add, it is usual to provide a second denominational selector, also traveling with the carriage. If these two selectors are set at letter-spaces closer 65 together than the number of computing wheels in the totalizer, one selector will become effective on the computing wheels forming the highest denominations of the totalizer, before the other selector has passed 70 from the highest down to and beyond the lowest computing wheels in said totalizer. This causes a digit sometimes to be set up simultaneously in two denominations at once. In order to avoid such inconvenience 75 and error, I have provided a device which is settable to silence certain wheels of said totalizer at will, so far as their connection to the numeral keys is concerned.

Other features and advantages will hereinafter appear.

In the accompanying drawings.

Figure 1 is a sectional side view of an Underwood-Hanson combined typewriting and computing machine showing so much thereof as is convenient for illustrating my invention as applied thereto.

Fig. 2 is a diagrammatic detail section showing a computation member in effective position to permit a digit pin thereon to be 90 set up if any numeral key is depressed at the moment.

Fig. 3 is a perspective view on a very much larger scale of part of the denomination selecting mechanism, showing my 95 invention as applied thereto.

Fig. 4 is a side view, partly in section, of Fig. 3.

Fig. 5 is a perspective view of a silencing plate.

Fig. 6 is a perspective view of a guide plate co-operating with the silencing plate, Fig. 5.

Fig. 7 is a diagrammatic view showing the relationship between a totalizer, carry-over devices and denomination selectors.

In the Underwood-Hanson combined typewriting and computing machine, alphabet keys 1 and numeral keys 2 when depressed, carry their key levers 4 downwardly, rocking bell cranks 5 to swing type-bars 6 carrying types 7, so that said types swing upwardly and rearwardly to print on a platen 8. Said platen forms part of the usual carriage 9 which is drawn forward in 10 letter-feeding direction by the usual spring barrel, (not shown), and is controlled by an escapement wheel 10, said escapement wheel being under the control of the usual dogs 11 which are swung by a universal bar 12, 15 so as to alternately engage the escapement wheel 10, said universal bar being operated by heels 13 on the type-bars, as said bars approach the platen. The escapement wheel 10 controls the carriage by means of a pinion 14 connected to said escapement wheel and meshing with a rack 15 connected to said carriage.

The numeral keys 2 of the typewriter as the carriage travels along in said machine, 25 set up digits written in a computing column on computation bars or members 16, by depressing a pin 17 on each of said bars, said pins each representing a digit, and there being one of the bars 16 for each denomination in which computing is done.

The bars 16 normally stand at the position shown in Fig. 1, where they are out of the reach of pin-setting bars 18, which bars are depressed whenever a numeral key 35 is operated. In the adding zone, however, the computation bars 16 are raised one after another, as shown in Fig. 2, so that the pins 17 thereon, will be within the reach of the pin-setting bars 18, with the result that 40 when any numeral key is actuated viz., depressed, its pin-setting bar 18 will depress its one of the pins 17 which is on the computation bar 16 raised at the moment to pin-setting position.

45 To thus lift the computation members or pin-bars 16, there is provided on the typewriter carriage a tappet 19, mounted on an arm 20, which arm is settable along the bar 21, on which it is pivoted, said bar forming 50 part of a bracket frame 22, fast on the rear side of the typewriter carriage. The tappet 19 is held against shifting on the bar 21 by a rack bar 23, which is engaged by the rear end of an extension 24 of the arm 20.

55 As the tappet 19 travels along with the typewriter carriage, it lifts the computation members 16 one after another, by means of jacks 25, which it rides under and lifts one at a time, camming the forward ends 60 up from the position seen in Fig. 1 to the position seen in Fig. 2, swinging said jacks around the bar 26 on which they are pivoted, so that the rear end of any jack which has been elevated by the tappet 19 presses down

a wire or rod 27 at the rear side of the typewriter machine, with the result that said rod through the lever 28 at the bottom thereof, which operates through the usual transposition device 29, will raise the computation bar or member 16 from the position 70 seen in Fig. 1 to the position seen in Fig. 2, thus permitting any pin to be set thereon as described above.

The operation of the pin-setting bars 18 is effected from the numeral keys by means 75 of pendants 30, of which there is one on each numeral key, and each pendant when it descends, strikes its own rock arm 31, which rock arm is fast on the forward end of a shaft 32, and this shaft, by means of a rock arm 33 fast thereon, operates the pin-setting bar 18. This it does by means of a linkage including bell cranks (not seen), and an operating bar 34, co-operating with said bell cranks and pin-setting bar 18, to form a 85 linkage for setting the pins.

When a series of pins have been thus set up on computation bars 16, the numbers represented by them are carried into the computing wheels 35 at the front end of the 90 machine, this being done by means of a general operator including a cross bar 36, which comes forward and strikes the portion of any pin which is depressed below the bottom of the computation bar 16 and thereby drives each computation bar 16 to an extent depending on which pin has been depressed thereon.

Each bar 16 drives its computing wheel by means of a rack 37 on its front end, 100 which rack bar meshes with a pinion 38 on the computing wheel. On the return stroke of the general operator, the computation bars 16 are returned by the cross-bar 36 which is effective on lugs 39, forming parts 105 of said bars. The computing wheels are not, however, turned backward by the racks 37 because of pawl-and-ratchet connections between them and said rack bars. At the end of the return stroke of the general operator, all the set pins are restored to their normal ineffective position by means of the usual pin-restoring plate 40 which is momentarily raised against the bottom of the computation bar 16.

As described in the fore part of this specification, one of the objects of the present invention is to provide means whereby certain of the computing wheels will be unaffected by the numeral keys of the typewriter. To bring about this result, I have shown certain of the rods 27 which are operated by the tappet 19 through the jacks 25, as movable to a position clear of their jacks, so that said jacks will be ineffective on their rods, and therefore the tappet 19 will be ineffective on certain bars 16. For this purpose, I have provided a special guide plate

41, (Fig. 5), for certain of the rods 27, and I use this to move these rods to a position where the jacks 25 will be ineffective on them. The rods 27 which are not to be so moved, are provided with a separate guide plate 42, Fig. 6.

When the special guide plate 41 is actuated to carry the rods 27 which it actuates, to position clear of their jacks 25, said guide plate is moved rearwardly from the position seen in Figs. 1, 2, and 3 to the position seen in Fig. 4, in which position the nearest rod 27 stands clear of its jack 25. The rods 27 seen in the rear in Fig. 4, pass through holes 43 in the guide plate 42, said guide plate being fixed to a bracket 44, fast on the casing 45 surrounding the jacks 25. This casing is usually fixed to a cross-bar 46 fast to a rearwardly extending bracket 47 attached to the frame of the typewriter. Thus the rods 27, which pass through the holes 43 are permanently held in position where the jacks 25 will be effective on them.

As illustrated herein, six of the nine rods 27 pass through the guide holes 43 in the fixed guide plate. The three remaining rods 27 pass through openings 48 and 49, said openings extending to the edge of the plate 42, thus permitting the rods to move freely back and forth in said opening.

The special sliding guide plate 41 is provided with three guide holes 50 through which the rods 27 pass, which are to be moved to the position clear of the jacks 25. This slideable guide plate 41 is a flat piece of metal having downwardly and inwardly bent ears 51 at the opposite ends thereof, which engage and embrace the inwardly bevelled ends 52 of the fixed guide plate 42. Thus the fixed plate forms a guide for the sliding plate. A large portion of the plate 41 is cut-away as at 53 so that said plate has an opening large enough to allow it to move idly with respect to the rods 27 which pass through the fixed guide openings 43.

For convenience in adjusting the mechanism, there is provided a handle 54, forming the upper end of a lever pivoted at 55, of which the downwardly extending portion 56 enters an opening 57 in the guide plate 41 to move said plate. Thus said handle forms an easy means of shifting the guide plate 41 to one position or the other. Said handle may be locked in either its rearward or its forward positions, by means of a detent arm 58, said arm comprising two notches 59, adapted to catch the handle 54 in either position. Said handle is sufficiently springy so that it may be easily sprung out by the finger of the operative from either of the notches 59 in which it is caught, and may then be shifted to engage the other notch.

In order to have a guide for the lower end of the arm 56, there is provided an elongated

notch 60 in the fixed guide plate 42 which 65 steadies said arm 56 and helps to make it shift the slideable guide plate 41 to slide without jamming.

In order to insure that the slideable rods 27 shall never catch behind their jacks 25, 70 said jacks are provided at their rear ends with cam pieces 61 extending upwardly and rearwardly from the ends of said jacks where they usually rest on said rods. In Fig. 4 the jack of one of the shiftable rods 75 27 is shown as being elevated when its rod is clear of said jack, with the result that said rod is moved idly.

Since my mechanism silences only the rods 27, but leaves the carry-over mechanism 80 of the usual Underwood-Hanson machine unaffected, it will be seen that if the total of the numbers written and added is large enough to run over from the computing wheels selected by the rods 27 into the other 85 computing wheels by carry-overs, said running-over will be properly computed because, in my invention, the usual Hanson carrying-over mechanism has in no way been changed. Said Hanson carry-over mechanism is fully disclosed in the patent to Hanson 90 816,319, wherein the carry-over wheels 62 are described as set by the computing wheels 35 and driven *seriatim* by a drive shaft 63 on the return stroke of the general 95 operator.

Though I have shown the machine as set only for cross-adding, my invention is equally applicable to machines for footing in each of several narrow adjacent columns 100 on different totalizers; one method of arranging tappets, rods and jacks for cross-adding being shown in the co-pending application of Frederick A. Hart No. 466,836, filed December 10, 1908. By limiting the 105 number of denomination rods on which the tappets are effective in commercial machines of that type which have nine computing wheels per register, two adjacent columns of eight letter-spaces each, can be footed in adjoining columns, and the denomination bars of only one totalizer will be effective at any 110 one time.

In the machine herein illustrated, I have shown nine rods 27 which correspond to nine 115 computing wheels of a single totalizer, and these rods are shown as spaced apart at certain letter spaces for pointing off between dollars and cents, and between hundreds and thousands of dollars, and between hundreds 120 of thousands and millions, and between hundreds of millions and thousands of millions. These letter-spaces provide for the writing of commas and periods in such spaces.

To illustrate how my invention may be 125 used in extreme cases, I show below, how items of dollars and cents can be added in two columns separated by a single column in

which non-computed numbers are printed. Tappets set for this are shown in the lower part of Fig. 7.

	Item.	No.	Item.
5	\$		\$
	5,321.00	1	5,346.00
	1,421.00	2	1,213.12
	etc.	3	etc.
10		4	
		5	
		6	
		7	

It will be noted that if the full set of jacks had been used while writing said numbers, not only would the non-computed numbers have been added in somewhere, but also certain numbers of one column would have been added in at some irregular place in the other column because two denomination selectors would be effective at different points on the same array of jacks at the same time. Also with the silencing handle in effective position, two adjacent or non-adjacent wide columns can be added in the same way on this machine without such non-computed numbers between them as below.

	Item.		Item.
30	\$		\$
	5,321.00		5,346.00
	1,421.00		1,213.12
	etc.		etc.

It will be observed that this example is only given to illustrate one of the uses of my mechanism, and such an extreme example is selected simply because it emphasizes points which might otherwise require examples of long columns of addition to properly illustrate the points.

Variations may be resorted to within the scope of the invention, and portions of the improvements may be used without others.

Having thus described my invention, I claim:

1. In a combined typewriting and computing machine, the combination with a traveling carriage and a totalizer comprising a considerable number of wheels, a series of denomination selectors connected to be operable with said carriage for selecting said wheels, and a finger-piece settable to make said selectors ineffective at will on a certain group of said wheels of said totalizer, while remaining effective on the remaining wheels, whereby the denomination selectors may be arranged to operate in closer succession, to permit closer spacing of typewritten columns on the work-sheet.

2. In a combined typewriting and computing machine, the combination with a traveling carriage and a totalizer comprising a considerable number of wheels, a series of denomination selecting tappets operable

concomitantly with said carriage for selecting said wheels, jacks operated by said tappets, one jack for each wheel, and a finger-piece settable to make certain jacks ineffective at will on said wheels, while the other jacks remain effective on their wheels, whereby the tappets may be arranged to operate in closer succession, to permit closer spacing of typewritten columns on the work-sheet.

3. In a combined typewriting and computing machine, the combination with a traveling carriage and a totalizer comprising a considerable number of wheels, a series of denomination selecting tappets operable concomitantly with said carriage for selecting said wheels, jacks operated by said tappets, a rod for each wheel, coöperating with the jack for its wheel, a guide for said rods, and an auxiliary guide for shifting certain of said rods to a position clear of their jacks.

4. In a combined typewriting and computing machine, the combination with a traveling carriage and a totalizer comprising a considerable number of wheels, a series of denomination selecting tappets operable concomitantly with said carriage for selecting said wheels, jacks operated by said tappets, a rod for each wheel, each under-lying its jack for its wheel, a guide for certain of said rods, a special guide for the remainder of said rods adapted to swing them clear of their jacks, and cam extensions on said jacks adapted to be struck by said rods when returning from a position clear of their jacks and adapted to lift said jacks above their rods.

5. In a combined typewriting and computing machine, the combination with a traveling carriage and a totalizer comprising a considerable number of wheels, a series of denomination selecting tappets operable concomitantly with said carriage for selecting said wheels, jacks operated by said tappets, a rod for each wheel coöperating with the jack for its wheel, a guide for said rods, an auxiliary guide for shifting certain of said rods to a position clear of their jacks, and a finger-piece for setting the guide for said shiftable rods to hold the rods in either effective or ineffective position.

6. In a combined typewriting and computing machine, the combination with a traveling carriage and a totalizer comprising a considerable number of wheels, a series of denomination selecting tappets operable concomitantly with said carriage for selecting said wheels, jacks operated by said tappets, a rod for each wheel, each under-lying its jack for its wheel, a guide for certain of said rods, a special guide for the remainder of said rods adapted to swing them clear of their jacks, cam extensions on said last

mentioned jacks adapted to be struck by their rods when returning from a position clear of their jacks and adapted to lift said jacks above their rods, and a finger-piece for setting the guide for said movable rods to hold them in either effective or ineffective position.

7. In a combined typewriting and computing machine, the combination with a traveling carriage and a totalizer comprising a considerable number of wheels, a series of denomination selectors connected to move concomitantly with said carriage for selecting said wheels, and a finger-piece settable to make said selectors ineffective on certain of said wheels.

8. In a combined typewriting and computing machine, the combination with a series of jacks and a denomination selector for selecting them *seriatim*, of denominational rods on which said jacks are effective, a plate comprising a guide for certain of said rods holding them so the jacks will be effective on them, a second plate comprising a guide for the remainder of said rods, and a finger-piece for shifting said second guide to carry its rod clear of their jacks.

9. In a combined typewriting and computing machine, the combination with a series of jacks and a denomination selector for selecting them *seriatim*, a plate comprising a guide for certain of said rods holding them so the jacks will be effective on them, a second plate slideable on said first plate and embracing it and forming a guide for the remainder of said rods, and a finger-piece which shifts said second guide to carry its rods clear of their jacks.

10. In a combined typewriting and computing machine, the combination with a denomination selector and a series of jacks, of denominational rods associated with said jacks, a guide plate for certain of said jacks, a second guide plate embracing all said jacks but movable idly with respect to certain of them but adapted to move the remainder, a finger-piece comprising a lever adapted to move said second guide plate, and an extension of said lever working in an opening in said first-named guide plate to steady said lever.

11. In a combined typewriting and computing machine the combination with a carriage and a totalizer comprising a number of wheels, of a series of denomination-selecting tappets operable concomitantly with said carriage for selecting said wheels, jacks operated by said tappets, a rod for each wheel coöperating with the jack for its wheel, certain of said rods being shiftable into and out of position to clear the jacks, and a key to shift said shiftable rods.

12. In a combined typewriting and computing machine, the combination with a carriage and a totalizer comprising a series of wheels, of denomination selectors connected to move concomitantly with said carriage for selecting said wheels, and a finger piece operable at will to make said selectors ineffective on the highest of said wheels and certain adjoining wheels, to thereby reduce the range of travel of the carriage within which a selector is operative on the series of wheels, said selectors being relatively adjustable toward and from each other, so that when the highest wheels are to be selected the selectors may be correspondingly spaced apart, and when the selectors are not to select the highest wheels they may be close together.

13. In a combined typewriting and computing machine, the combination with a traveling carriage to determine the zones of writing and computing, of a totalizer comprising a considerable number of computing wheels for computing numbers written, carry-over devices for said wheels constantly connecting them all to form a carry-over train, a series of denomination selectors connected to be operable with said carriage for selecting said wheels *seriatim* in accordance with the travel of said carriage, a finger-piece, and means shiftable thereby to make said selectors ineffective for selecting the highest of said wheels and certain adjoining wheels, thereby to reduce the effective number of the selectors without making a corresponding reduction in the capacity of the totalizer.

14. In a combined typewriting and computing machine, the combination with a traveling carriage to determine the zones of writing and computing, of a totalizer comprising a considerable number of computing wheels for computing numbers written, carry-over devices for said wheels constantly connecting them all to form a carry-over train, a series of denomination-selecting tappets operable concomitantly with said carriage for selecting said wheels in accordance with the travel of said carriage, jacks operated by said tappets, one jack for each wheel, a finger-piece, and means shiftable thereby to make the jack for the highest wheel and jacks for certain adjoining wheels ineffective for their wheels, thereby to reduce the effective number of the jacks without making a corresponding reduction in the capacity of the totalizer.
